UNITED STATES PATENT OFFICE.

ROSE M. BERRENT, OF NEW YORK, N. Y.

DESIGN FOR A POST SERVICE-BADGE.

53,982.

Specification for Design.

Patented Nov. 4, 1919.

Application filed February 26, 1919. Serial No. 279,449. Term of patent 7 years.

To all whom it may concern:

Be it known that I, ROSE M. BERRENT, a citizen of the United States, and a resident of the city of New York, borough of Manhattan, in the county and State of New York, have invented a new, original, and ornamental Design for a Post Service-Badge, of which the following is a specification.

The figure is a face view of a badge showing my new design.

I claim—

The ornamental design for a post service badge as shown.

ROSE M. BERRENT.
